US0D1071175S

(12) **United States Design Patent** (10) Patent No.: **US D1,071,175 S**
 Timms et al. (45) Date of Patent: ** Apr. 15, 2025

(54) **POD CARRIER FOR DEODORIZING AGENTS**

(71) Applicant: **Emory University**, Atlanta, GA (US)

(72) Inventors: **Cynthia Glenn Timms**, Atlanta, GA (US); **Ronald Lloyd Bracken**, Monroe, GA (US); **George Louis Cavagnaro, Jr.**, Atlanta, GA (US)

(73) Assignee: **Emory University**, Atlanta, GA (US)

(**) Term: **15 Years**

(21) Appl. No.: **29/878,720**

(22) Filed: **Jun. 27, 2023**

Related U.S. Application Data

(62) Division of application No. 29/705,380, filed on Sep. 11, 2019, now Pat. No. Des. 1,010,812.

(57) **CLAIM**

The ornamental design for a pod carrier for deodorizing agents, as shown and described.

DESCRIPTION

FIG. 1 is a top perspective view of a pod carrier for deodorizing agents showing our claimed design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right-side view thereof; and,

FIG. 8 is a left-side view thereof.

The broken lines in the drawings show portions of the pod carrier for deodorizing agents that form no part of the claimed design.

1 Claim, 6 Drawing Sheets
